H. J. CASE AND F. I. JOHNSON, OF SUGAR GROVE, PENNSYLVANIA.

Letters Patent No. 77,252, dated April 28, 1868.

IMPROVED WASHING-MACHINE.

The Schedule referred to in these Letters Patent and making part of the same.

TO ALL WHOM IT MAY CONCERN:

Be it known that we, H. J. CASE and F. I. JOHNSON, of Sugar Grove, in the county of Warren, and State of Pennsylvania, have invented certain new and useful Improvements in Washing-Machine; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention relates to washing-machines, and consists in the novel arrangement of two peculiarly-grooved rollers over one that is stationary, in such a way that they may operate and adjust themselves to the article or articles being washed, independently of each other.

In the drawing—

Figure 1 is a longitudinal vertical sectional view of our machine.

In constructing our machine, we make an oblong rectangular box, A, of any desired size, and mount in supports i, placed on each side of the box A, and fastened to it, a large grooved roller, B, as shown in the figure. The crown of the supports i we make circular, and so as to be on a line with the outer ends of the teeth of the roller B, as shown in dotted lines. In the corners of the box A, we place braces G and H, both to strengthen the box, and as supports for the arms E and F, which are hinged to them at a and b, and which extend to the middle of the box, and have pivoted between their outer ends the rollers C and D, grooved, so as to correspond with the grooves in the large roller B. The arms E and F, when in position, are arranged so that their upper sides shall be flush with the upper edge of the box A, except at their outer ends, which incline upward, as shown in the drawing. The extreme outer ends of these arms E and F, we connect with cross-pieces c and d. As the roller C is pivoted or mounted between the outer ends of the arms E, which are hinged in the braces G, and as the roller D is similarly arranged between the arms F, they thus move independently of each other. The roller C may be raised by the cross-piece c, and thrown back, as shown in dotted lines in the drawing, and the roller D may continue to operate, and it, too, may be raised and thrown up. The rollers C and D are smaller than the roller B, as shown in the drawing. Their grooves, however, are made to correspond with those in the roller B, and with each other, and are of a novel form, their base, h, being flat, or nearly so, their sides g, also flat, and at right angles with the length of the rollers, and their extreme outer lines rounding. We have found that grooves made in this form do not injure the clothes or articles that pass between them, especially when there are hooks or buttons upon them.

The braces or supports H we extend above the upper side of the box A, and mount therein rubber rolls I and J, or rolls covered with rubber or any substance suitable for ringers. The journals of the upper roller I turn in bearings arranged to move vertically in slots in the supports H. These bearings are held in place and made adjustable automatically by a metal spring, e, or any other suitable device. Across the upper ends of the supports or standards H we attach a cross-bar, f, to strengthen them, as well as to prevent their spreading.

To the roller B we attach a crank, which is upon the outside of the box A, and to the roller J we also attach a crank, which is on the outside of the brace, support, and standard H.

In operating our machine, we fill the box A with water to the desired height, put the clothes or other articles to be washed into it, and draw them backward and forward through or between the rollers B, C, and D, by giving the roller B a rapid reciprocating motion, and thus thoroughly washing the articles.

As the rollers C and D are pivoted in separate arms, E and F, each will move and adjust itself to the substance interposed between it and the roller B, independent of the other, and for this reason will operate more effectually and with greater advantage than they can do when attached to the same arms hinged at one end of the box.

The cross-bars c and d, connecting the outer ends of the arms E and F, support and strengthen and secure steadiness in the motion of the small rollers C and D between them; and, when it is desired, the operator can press with his hand upon the bars c and d, and thus cause the rollers to rub upon the interposed substance as

d as may be necessary to secure thorough washing, or, if he wishes, a weight may be placed upon them for same purpose.

The clothes, when washed, we pass between the wringing-rolls I and J, which completes the operation.

We have found, by actual experiment, that a washing-machine constructed in this way is very effectual in operation, washing the lightest as well the heaviest articles rapidly, thoroughly, and without the usual injury to the fabric caused by many other machines.

Having thus described our invention, what we claim, is—

An improved washing-machine, consisting of a box, A, having mounted therein the grooved roller B, in combination with the grooved rollers C and D, mounted respectively in the arms E and F, hinged independently of each other, and provided with the cross-bars c and d, all constructed and arranged to operate substantially as herein described.

H. J. CASE,
F. I. JOHNSON.
